UNITED STATES PATENT OFFICE.

EUGENE SCHREIBER, OF PORTLAND, OREGON, ASSIGNOR TO FERRIS STOVE-TOP COMPANY, OF PORTLAND, OREGON, A CORPORATION OF OREGON.

TOP PLATE FOR GAS STOVES.

Application filed September 2, 1924. Serial No. 735,328.

This invention relates to improvements in top-plates for cooking-stoves or ranges using gaseous fuel. Heretofore gas-stoves and ranges have been commonly constructed with tops comprising a metal grating of relatively open construction allowing of the escape of a great deal of the heat from the burners about the pots placed thereover. Plate-tops for gas-stoves have been widely adopted to remedy these losses and disadvantages and some have been provided with depending bands about their pot-holes to conserve the heat and make the same more effective in the heating of limited portions of the top. These latter devices are apt to subject the top-plate of the stove to severe internal stresses due to the unequal heating of the top which frequently results in the cracking of the plate or its becoming warped.

It is the object of my invention to provide a top-plate of simple and novel construction provided with a pair of pot-holes and means to confine the heat generated from a burner to the immediate portions thereabout with communication between two adjoining pot-holes together with means for the protection of the plate from the relatively extreme localized expansion and contraction caused by the confinement of the heat to the middle portions of the plate.

A further object of my invention resides in the provision of a lid for the pot-holes of my improved top-plate having a substantially plane lower surface and an aperture to receive a lifting handle with novel means to admit of the entrance of said lifter at all times into said aperture when the lid is resting upon a flat surface.

Other objects and advantages, and objects relating to various parts and details of construction will be readily apparent in the detailed description to follow.

In the accompanying drawings I have plainly shown by way of example one form in which my invention may be constructed, and herein—

Figure 1 is a view in longitudinal section of a top-plate embodying my invention shown mounted in operative position upon a stove.

Fig. 2 is a view in transverse cross-section of the same.

Fig. 3 is an underside plan view of my improved top-plate, detached.

Fig. 4 is an underside perspective view of a lid element of the invention.

Fig. 5 is a detached perspective view of a holding clip employed in the invention.

Referring to said views, the reference numeral 1 indicates the parallel side bars of the top-frame of a gas-stove, and 2 the end-bars thereof which are usually integrally connected together at their ends in a single casting. Said bars are usually of angle configuration in cross-section and are formed along the inner marginal edge of their horizontal flanges 3 with a reentrant angular groove 4 in which a grating, not shown, was designed to be supported.

The top-plate of my invention comprises a body 5 of rectangular configuration having parallel plane upper and lower surfaces 6 and 7, respectively. A marginal depending bead 8 extends about said plate designed to support the plate upon the upper surface 10 of the stove-bars 1 and 2 exteriorly of the groove 4.

At one end 11 of the plate oppositely curved ribs 12 are symmetrically formed on the underside extending from the bead 8 at the end of said plate to the bead at the side marginal edges, respectively. Said ribs are spaced apart at their outer ends to provide an intermediate handle-portion 13 formed with a plurality of slots 15 parallel with the transverse axis of the plate. Similar slots 16 are formed in the corner portions 17 exteriorly of said ribs 12. Said slots 16 serve to weaken the plate at such corner portions so that the plate may be broken away more readily along the line of one of said slots selectively and along the outer margin of a rib 12 to more perfectly adapt it to fit the tops of stoves of different lengths should the need arise and accommodate a stove-pipe. In Fig. 3 I have shown the top in full lines broken away as described, and in broken lines with the top-plate in its original condition. To fit the plate onto a stove-top having a stove-pipe one entire corner-portion 17 may be broken away to fit the stove-pipe, or as much thereof as necessary.

In the event that the portions are removed from the top-plate, as shown in Fig. 3, the handle-portion 13 will extend beyond the stove-bar 2 and provide a convenient means for lifting the plate.

Numerals 18 indicate clip attachments formed with a slotted hole 19 through which

they may be secured to the underside of the plate in adjusted positions by means of bolts 20 projecting through the plate. An offset end 21 extends downwardly at their 5 outer ends and bears against the side bars 1 at each side to maintain the plate in rigid position relative to the stove. The bolts 20 located near the end 22 of the plate are extended through apertures in the plate body 10 5 and the similar bolts at the other end of the plate extend through any of the slots 16 desired.

The plate body 5 is provided with a plane upper surface 6 and is formed with a pair of 15 pot-holes 23 and 24 of the usual circular configuration arranged symmetrically in the major axis of the plate. Dependent flanges 25 are formed about the inner marginal edge of each said pot-hole providing a ledge upon 20 which lids 26 may be lodged with their upper surfaces flush with the upper surface 6 of the plate. Said flanges 26 depressed below the plane of the lower surface 7 of the plate are connected by a pair of ribs 27 25 extending convergently from the hole 23 toward the hole 24, that is to say, toward the end 11. Said ribs, cast integrally with the flanges 25 and the plate generally, are substantially tangent to the flanges about the 30 hole 23 and are directed to intersect at a point within the end 11 of the plate so that a considerable contraction of the passage 28 is afforded therebetween in the distance between the two pot-holes.

35 An effectively continuous band 30, preferably of sheet metal, is secured to said plate by bolts 31 following the circular contours of said pot-holes outwardly of their junction with the ribs 27 and extending in similar convergent directions upon the outside 40 and in close engagement with said ribs. Being upon the outside of said flanges 25 and said ribs 27 and in close contact at its upper edge with the under surface 7 of the plate 45 a reasonably gas-tight joint is provided thereat and the depth of the band, approximately an inch in width, assures that but little heat is lost except by radiation.

The lids 26 are desirably formed with 50 parallel plane surfaces on their opposite sides. An aperture 32 is formed contiguous to the peripheral edge of each lid and adjacent thereto upon the under side and symmetrically in a radial line interiorly thereof 55 is formed or provided with a lug 33 having a flat lower end upon which the lid will rest in tilted condition when lying on a flat surface, such as the stove-top when removed from its pot-hole and whereby the end 34 of 60 a stove-lifter 35 may be easily entered into the aperture 32 which is thus elevated above the supporting surface.

It will be seen that the holes 23 and 24 are connected by a continuous band 30 which

will tend to prevent the dissipation of the 65 heat generated from the burning of gas emitted from the burners, shown at 36 in Fig. 1. If but one burner is in operation a considerable portion of the heat therefrom, instead of flowing radially therefrom and under a pot or lid resting thereabove to be 70 wasted, will flow from one pot-hole to the other through the passage 28 and become effective to supply heat to a utensil held over the other hole. Similarly the entire 75 portion of the top plate including the lids 26 comprised within the portion thereof delimited by the band 30 will become heated sufficiently to cook food from the heat supplied by one burner and with two burners 80 still greater results may be obtained with both burners turned comparatively low.

With the heat being confined in the manner described within said band 30 and with the relatively cooler portions of the 85 plate outside of said band a considerable difference of temperature will result in a variation of expansion and contraction of the metal in the plate-top, and frequently causes the cracking and warping of the top adjacent 90 said band. To guard against this effect I have provided the ribs 27 to reinforce the plate upon the line of the greatest stress in molecular disturbance and which does 95 efficiently prevent such defects as the cracking and warping of the plate at such regions.

I wish it to be understood that my invention is not limited to the use of all of the above described features and constructions, for some may be omitted and others may be 100 varied or modified in various ways, as will be readily apparent to those skilled in the art.

Having described my invention, what I 105 claim as new, is:

1. A top-plate for stoves, comprising a plane horizontally extending plate having a pair of pot-holes formed therein, marginal depressed flanges about said holes, a pair of ribs integrally formed on the underside of said plate and connecting said flanges integrally at their adjacent sides, and a depending band connected on the underside of said plate in close alignment with said ribs and said flanges exteriorly of said ribs.

2. A top-plate for stoves, comprising a plane horizontally extending plate having a pair of pot-holes formed therein, marginal depressed flanges about said holes, a pair of convergent ribs integrally formed on the underside of said plate and connecting said flanges integrally at their adjacent sides, and a depending band connected on the underside of said plate in close alignment with said ribs and said flanges exteriorly of said 115 ribs.
